ration of Illinois

Application March 23, 1942, Serial No. 106,282

Term of patent 7 years

To all whom it may concern:

Be it known that I, Moe Greendale, a citizen of the United States, residing at Chicago, Cook County, and State of Illinois, have invented a new, original, and ornamental Design for a Tucked Skirt, of which the following is a specification, reference being had to the accompanying drawing, forming part thereof.

Fig. 1 is a front elevation of a tucked skirt laid out flatwise, showing my new design, and

Fig. 2 is a rear elevation thereof laid out flatwise.

The characteristic feature of my design resides

in the combination on the skirt disclosed of the cross-wise extending, super-imposed strips of piping intersecting the full length tucks which extend from the waistband to the lower edge of the skirt, in association with shorter tucks between the full length tucks, and which shorter tucks extend from the waistband to the lower edge of the uppermost strip of piping, all as shown.

I claim:

The ornamental design for a tucked skirt, as shown and described.

MOE GREENDALE.
